UNITED STATES PATENT OFFICE.

CHARLES L. SHEPPY, OF BUFFALO, NEW YORK, ASSIGNOR TO THE PIERCE-ARROW MOTOR CAR COMPANY, OF BUFFALO, NEW YORK.

METHOD OF AND MEANS FOR SEALING SLEEVES IN THE JACKETS OF ENGINE-CYLINDERS.

1,285,430.

Specification of Letters Patent. Patented Nov. 19, 1918.

Application filed January 10, 1917. Serial No. 141,727.

To all whom it may concern:

Be it known that I, CHARLES L. SHEPPY, a citizen of the United States, residing at

Buffalo, in the county of Erie and State of New York, have invented a new and useful Improvement in Methods of and Means for Sealing Sleeves in the Jackets of Engine-Cylinders, of which the following is a specification.

10 This invention relates to a method of and means for sealing the joints between the inner sleeves and the water jackets of the cylinders of internal combustion engines of that sort in which the cylinder is formed by 15 a separate tube or sleeve of steel or other suitable metal secured in a jacket of suitable metal, such for instance as aluminum.

When the sleeve and jacket of these cylinders are made from different metals, such as 20 steel and aluminum, which have different coefficients of expansion, much trouble has been experienced in making the joints between the sleeve and jacket so that they will remain tight and prevent leakage, on account of the difference in expansion and 25 contraction of the two parts. Difficulty has also been experienced in multiple cylinder engines of this sort in which a plurality of cylinder sleeves are used in a single 30 jacket casting, due to the fact that the casting is not as rigid in the direction of its width as in a lengthwise direction and when the cylinder sleeves are driven into the sleeve cavities of the casting the jacket castings frequently give in the direction of least 35 resistance and are thus distorted. This further adds to the difficulty of making and keeping the joints between the sleeves and jacket tight.

40 The object of the invention is to provide an efficient and reliable method of and means for insuring tight joints between the sleeves and jackets.

According to this invention, circumferential sealing grooves are provided at the 45 joints between the sleeve and jacket and these grooves are filled under pressure with a suitable semi-fluid or plastic material which effectually seals the joints.

50 In the accompanying drawings:—

Figure 1 is a longitudinal sectional elevation on line 1—1, Fig. 2 of an internal combustion engine cylinder in which the joints between the jacket and sleeve are sealed in 55 accordance with this invention.

Fig. 2 is a fragmentary plan view thereof, partly in horizontal section on line 2—2, Fig. 1.

Fig. 3 is an enlarged sectional elevation through the lower joint between the jacket 60 and sleeve, indicating by dotted lines the application of the pressure device for forcing the sealing material into the joint.

Fig. 4 is an enlarged sectional elevation showing the upper joint. 65

Fig. 5 is an inside elevation of a fragment of the jacket showing the sealing grooves therein.

Fig. 6 is a view similar to Fig. 3, showing a modified construction. 70

A represents the water jacket, B the inner sleeve, C the cylinder head of an internal combustion engine. These parts, except as to the means for sealing the joints between the sleeves and jacket may be of any usual 75 or suitable construction, and may be made of any suitable materials. Preferably, the jacket and cylinder head are aluminum castings while the sleeves B are made of steel having suitable qualities of strength and 80 durability. The jacket is provided at the upper and lower ends of the cavity for each inner sleeve B with portions 10 and 11 having cylindrical openings or bores in which the opposite ends of the inner sleeve fit, the 85 sleeve, being, as usual, driven into place in the sleeve cavity of the jacket. The jacket forms a water chamber or space 12 around the sleeve. The sleeve is preferably provided with a circumferential flange 13 at 90 its upper end which is secured between an internal shoulder 13^a at the upper end of the portion 10 of the jacket and the cylinder head C which is bolted or otherwise secured in place on the jacket, as usual. The upper 95 end of the inner sleeve is thus rigidly held and prevented from movement relative to the jacket. The joint between the opposite end of the sleeve and the portion 11 of the jacket is, however, cylindrical throughout 100 and this end of the sleeve is thus capable of movement relatively to the jacket, due to the difference in expansion and contraction of the metals forming the sleeve and jacket.

Each of the joints between each sleeve and 105 jacket is provided with one or more sealing grooves adapted to contain sealing material so that when these grooves are filled with the sealing material the joints between the sleeve and jacket will be effectually sealed 110

and rendered water tight. Two sealing grooves 14 are shown for the joint at the upper end of the sleeve, these grooves being formed half in the outer surface of the 5 sleeve and half in the inner surface of the part 10 of the jacket. Three sealing grooves 15 are shown for the lower joint, these grooves being preferably formed only in the inner surface of the part 11 of the jacket, 10 thus leaving the coöperating surface of the inner sleeve cylindrical and smooth to permit of the relative movement of the sleeve in the jacket. Any required number of the sealing grooves, one or more, may be employed 15 for each of the joints. The sealing grooves 14 for the upper joint are connected at one side of the sleeve by a groove 16 with a filling hole 17, leading out through the jacket, and at the opposite side of the sleeve 20 the sealing grooves are preferably similarly connected with a vent hole 18 leading out through the jacket. The sealing grooves 15 for the other joint are similarly connected with filling and vent holes 19 and 20 respectively. Each of the vent holes is closed by 25 a screw or plug 21 of any suitable sort adapted to tightly close the vent hole. Each of the filling holes is preferably provided between its ends with a valve seat or shoulder 22 and the portion of the filling hole located outwardly beyond this seat or shoulder is screw-threaded to receive a screw plug or valve 23 which has an inner end of conical or other suitable shape adapted to seat 30 against the shoulder 22 when the screw is screwed in for tightly closing the filling hole. Each filling hole is provided with a branch filling passage 24 which leads from the hole at a point outwardly beyond the 35 valve seat 22 to the exterior of the jacket and the outer end of this passage is screw-threaded or otherwise adapted for the connection therewith of a screw pump or other device, indicated by dotted lines at 25 in Fig. 3, for forcing sealing material into the filling hole and the sealing grooves connected therewith.

In the modified construction shown in Fig. 6, the filling passage 24^a for the connection 50 of the filling gun or device is formed by a hole in the screw plug or valve 23^a itself and connects with the filling hole through one or more orifices 24^b in the plug. In this construction the screw plug is unseated for filling 55 the sealing grooves and is seated for closing the filling hole, as in the case of the first construction described.

Each joint is sealed in the following manner:

60 The vent plug 21 is loosened or removed to permit the escape of air from the sealing grooves and the valve plug 23 is loosened or screwed off of the seat 22 of the filling hole, as shown in Fig. 3. A high pressure screw gun or other forcing device is then applied

to the filling passage 24 or 24^a and operated to force the sealing compound into the sealing grooves. As the material is being forced into the grooves the air can escape from the vent hole at the opposite side of the jacket 70 and when the sealing material appears at this hole the plug 21 is screwed in to tightly close the vent hole. The pressure on the material is continued until the grooves are filled with the sealing material and there is 75 no drop in pressure. The screw plug or valve 23 or 23^a is then screwed onto its seat, thus closing the sealing grooves and retaining the sealing material under pressure in the grooves. The filling device is then removed. The sealing grooves can thus be filled with sealing material under the necessary pressure to insure an absolutely tight and reliable joint.

The sealing material can be of any suitable 85 composition which is adapted to be forced under pressure into the sealing grooves and which will effectually seal the joints. Various different materials may be employed, depending on the duty required. In some cases 90 a compound can be used that will solidify. In other cases a compound that will not become hard will be found better. Sleeves sealed as described can be removed and resealed, or old sleeves can be resealed and 95 made tight.

I claim as my invention:—

1. The method of sealing the joints between the inner sleeves and outer jackets of engine cylinders in which the sleeve and 100 jacket have different coefficients of expansion and the ends of the sleeve fit in opposite openings in the jacket, consisting in forming a circumferential sealing groove between the sleeve and jacket at the joint 105 and a connecting filling hole, filling said groove under pressure with a sealing material, and closing the filling hole of the groove while the pressure is maintained.

2. The method of sealing the inner sleeves 110 in the water jackets of engine cylinders in which the sleeve and jacket have different coefficients of expansion, consisting in providing openings in the opposite ends of the jacket in which the ends of the sleeve fit, 115 securing one end of the sleeve to the jacket to prevent relative movement of said end of the sleeve in the jacket, the opposite end of the sleeve being capable of movement in its opening due to expansion and contraction 120 of the parts, providing circumferential sealing grooves between the opposing surfaces of the sleeve and the walls of said openings, and forcing a sealing material under pressure into said grooves.

3. The combination of the inner sleeve of a cylinder, an outer jacket surrounding said sleeve and having opposite openings in which the ends of said sleeve fit, said jacket being enlarged interiorly between said 130

openings to form a chamber around said sleeve, a groove being formed around the sleeve between the opposing surfaces of the sleeve and the wall of one of said openings, 5 one of said parts having a filling hole connecting with said groove through which a sealing material is forced under pressure into said groove, and means for closing said filling hole and retaining the sealing material under pressure in said groove.

4. The combination of the inner sleeve of a cylinder, an outer jacket surrounding said sleeve and having openings in its ends in which said sleeve fits, said jacket forming a 15 chamber between its ends around the sleeve, sealing grooves being formed around the sleeve between the opposing surfaces of the sleeve and the walls of said openings, said jacket having filling holes through which 20 sealing material is forced into said grooves, and means for closing said filling holes and retaining a sealing material in said grooves.

5. The combination of the inner sleeve of a cylinder, an outer jacket surrounding said 25 sleeve and having openings in its ends in which said sleeve fits, said jacket forming a chamber between its ends around the sleeve, means securing one end of the sleeve to the jacket to prevent relative movement of said 30 end of the sleeve in the jacket, sealing grooves being formed around the sleeve between the opposing surfaces of the sleeve and the walls of said openings, said jacket having filling holes through which sealing 35 material is forced into said grooves, and means for closing said filling holes and retaining a sealing material in said grooves.

6. The combination of the inner sleeve of a cylinder, a jacket surrounding said sleeve 40 and having an opening in which the sleeve fits, a sealing groove being formed around the sleeve between the opposing surfaces of

the sleeve and the wall of said opening, said jacket having filling and vent holes connecting with said sealing groove, and means for 45 closing said filling and vent holes and retaining a sealing material in said groove.

7. The combination of the inner sleeve of a cylinder, a jacket surrounding said sleeve and having an opening in which the sleeve 50 fits, a sealing groove being formed around the sleeve between the opposing surfaces of the sleeve and the wall of said opening, said jacket having a filling hole connecting with said sealing groove and provided with a 55 valve seat, a filling passage which connects with said hole outwardly beyond said valve seat and through which sealing material can be forced into said hole and groove, and a valve arranged to be seated on said seat for 60 closing said filling hole and retaining the sealing material in said groove.

8. The combination of the inner sleeve of a cylinder, a jacket surrounding said sleeve and having an opening in which the sleeve 65 fits, a sealing groove being formed around the sleeve between the opposing surfaces of the sleeve and the wall of said opening, said jacket having a filling hole connecting with said sealing groove and provided with a 70 valve seat, a filling passage which connects with said hole outwardly beyond said valve seat and through which sealing material can be forced into said hole and groove, and a plug which closes said filling hole outwardly 75 beyond its connection with said filling passage and is movable against said seat for retaining the sealing material in said groove.

Witness my hand and seal this 8th day of January, 1917.

CHARLES L. SHEPPY.
